UNITED STATES PATENT OFFICE

EDWARD N. JONES, OF PITTSBURGH, PENNSYLVANIA, ASSIGNOR TO THE C. O. BARTLETT & SNOW COMPANY, OF CLEVELAND, OHIO, A CORPORATION OF OHIO

METHOD OF RECONDITIONING CONCRETE AFTER TRANSPORTATION

Application filed March 27, 1928. Serial No. 265,102.

This invention relates to a method of reconditioning concrete at the point of delivery after transportation and consequent segregation of the same.

5 During the few years next preceding the date of filing of an application for Letters Patent on the invention herein described, in nearly all large cities there have been established central mixing plants in which concrete is mixed, and from which it is transported to the places of its use.

As ordinarily transported and delivered, the manufacturer of ready mixed concrete is compelled to restrict his product to stiff 15 mixes; that is, a mix having a water content so low that it is undesirably harsh and not sufficiently plastic for satisfactory use. This is particularly detrimental when concrete is desired of a consistency permitting it to flow 20 around reinforcing steel. When the wet concrete is transported and delivered in an ordinary manner, the mixture segregates; that is, the coarse aggregate gravitates to the bottom, while the grout, composed of sand, cement, 25 and water rises above the coarse aggregate.

When the body of the truck is inclined to unload the concrete, the grout containing the most important ingredient, the cement, runs off leaving the coarse aggregate, stone, slag, 30 or gravel packed in the bottom of the truck. This effect necessitates the use of pointed tools, and great effort, in order to dislodge this packed aggregate. It also necessitates a reconditioning of the concrete, by an additional mixing operation, in order that the concrete may be in proper condition for pouring.

The method of the present invention prevents the sticking of the coarse aggregate to 40 the bottom of the truck, by dumping the load from a collapsible container to the bottom of the truck at the time the concrete is to be unloaded.

Segregation occurs when concrete is transported in any vehicle, but by performance of the method described herein, this segregation is corrected when the mass is passed from a collapsible container to the bottom of the truck. The grout, which has risen to the top 45 during transportation of the wet concrete, is

worked back into the mixture through the crater formed in the mass of concrete, when it slides to the floor of the truck. When the truck body is inclined for dumping, and the concrete flows out, an additional remixing 55 and reconditioning step is performed.

The method of the present invention involves the principles of operation disclosed in my co-pending application Serial No. 205,588, filed July 19, 1927.

In the accompanying drawings Figure I is a cross sectional view through a truck body suitable for conducting the method of the present invention, showing the concrete supporting elements of the structure in carrying position; Figure II is a rear elevation of such truck body; Figure III is a diagrammatic cross sectional view, showing the position of the container elements during the transportation of concrete, and showing the condition of the concrete in the container after transportation; Figure IV is a similar view, illustrating the condition of the concrete during the initial stages of the collapse of the container and deposit of the concrete 60 on the true floor or bottom of the truck; Figure V is a similar view, illustrating a further progressive step in the deposit of the concrete, and remixing of its constituents; Figure VI is a similar view, illustrating the 65 final position of the container elements and the condition of the concrete after it has been wholly deposited on the floor of the truck; Figure VII is a plan view of the truck body, illustrating the flow of concrete from the truck body during the dumping action thereof; Figure VIII is a cross sectional view 70 through a modified form of truck body suitable for conducting the method of the present invention, showing the concrete supporting elements of the structure in carrying position; Figure IX is a diagrammatic cross sectional view, illustrating a position of the elements and condition of the material corresponding to the showing of Fig. IV; Figure X is a similar view showing a position 75 of the elements and condition of the material corresponding to the showing of Fig. V; and Figure XI is a similar view showing a position of the elements and condition of the material 80 corresponding to the showing of Fig. VI.

material corresponding to the showing of Fig. VI.

In the drawings the reference numeral 1 designates the true floor or bottom of the truck body, 2 the transverse members supporting the true floor or bottom, and 3 upright frame members of the body.

Container plates 4 and 5 each have a sliding engagement with members 6; and each are provided with means, indicated generally by reference numeral 7, for bringing the plates into the position of Figures I and III to form a container for concrete, and for controlling movement of the plates into the position of Figure VI to deposit the concrete on the true floor or bottom 1 of the truck body.

By reference to Figure III of the drawings, it will be noted that the grout A has risen through the coarser aggregate, and has been segregated to form the uppermost layer in the container B, formed by the plates 4 and 5. In this position the plates 4 and 5 are in mutual contact to form the container, with the edge of the plate 4 slightly overlapping the edge of the plate 5 at b.

The first step in the reconditioning and delivery of the concrete consists in separating, or permitting separation of, the lower portions of the plates 4 and 5. During this separating movement, the concrete is deposited on the floor as the support of the container plates is progressively withdrawn.

In the position shown in Figure IV, the coarse aggregate, which occupied the region adjacent the vertex of the container, has been already deposited on the bottom 1 of the truck body. This has permitted the material to sink along the longitudinal central line of the body, forming a crater C containing that portion of the grout A which has not penetrated the body of the coarser material by way of cracks formed therein by this initial movement.

As the separating movement continues there is a progressive folding and movement of the material into the crater C, in addition some masses D of the more solid material may detach themselves from the main body and fall into the crater; the crater C is thus filled, and the thinner material or grout, dispersed through the body of the coarser material. The progress of this remixing action is illustrated in Figure V of the drawings.

When the separating movement has been completed, as shown in Figure VI of the drawings, the weight of the concrete is almost wholly supported by the bottom 1 of the truck body. In this position substantially none of the grout remains at the surface of the mass, but is distributed throughout the entire body of coarser material.

It has been found that a better redistribution of the constituents is obtained if the separation of the plates 4 and 5 is gradual

rather than abrupt. This is for the reason that the mass is thus permitted to fold and fall in upon itself, and more opportunity is given for the grout to seep into and through the mass of aggregate. Any suitable means controlling the rate of the separating movement of the plates, such as the means disclosed in the above identified applications, may be employed for such purpose.

According to the method of the invention, the final step of delivering the concrete from the truck body is utilized to secure a final mixing action which insures a uniform distribution of the grout throughout the mass of aggregate. In order to effect this final working, the concrete is delivered through a relatively restricted opening.

As shown particularly in Figure II of the drawings, a horizontally extending platform 8 is permanently attached at the rear end of the truck and in line with the bottom 1 thereof. In order that the rearward extent of the platform may be varied at will, an extension 9 is hinged to the permanent platform portion 8. This hinged portion 9 normally assumes a vertical position, but may be supported by any suitable means in horizontal alignment with the permanent platform portion 8.

On the hinged platform portion 9 are angularly disposed stop bars 10, which converge rearwardly of this platform portion. Lying beneath the rear wall 11 of the truck body are a pair of hinged gates 12, which may be maintained in closed position by locking means 13. When locking means 13 are operated to release gates 12, the gates may be swung outwardly until their swinging movement is arrested by the stop bars 10. In this position they form a chute with converging walls and a restricted opening 14.

As the bottom 1 of the truck is tilted by any suitable means, the material is passed along the bottom 1 and through the aforesaid restricted opening 14 formed by the converging walls constituting the gate members 12. As the material meets the converging walls, and is directed to the opening 14, the material is caused to turn over on itself, and an additional working thereof is obtained. This additional working insures a uniform distribution of the materials, and avoids a possibility of retaining any of the grout in pockets throughout the mass of the material.

It will be understood that this additional working may be obtained by any suitable chute providing a constricted opening, and is not dependent upon the particular means shown for forming the same.

Figures VIII to XI inclusive illustrate the use of the particular form of body disclosed in the copending application above noted. In this form of truck body container plates 15 are movably mounted on side frame members 16, as by being hinged at 17 thereto. Actuating arms 18 are pivotally mounted in

bearings 19 along the sides of the outer structure of the truck and bear against the outer surfaces of the plates. Suitable means, indicated generally by reference numeral 20 5 are provided to act through arms 18 for bringing the container plates 15 into their carrying position, for supporting them therein, and for controlling movement of the plates during the deposition of the material 10 on the floor or bottom 21 of the truck.

It will be noted that in this modification the container formed by the plates 15 is elevated an appreciable distance above the floor 21. This makes some slight difference in 15 the movement of the material during its deposition on the floor, but produces approximately the same final result.

As shown in Figure IX a crater C' is formed during the initial separation of the 20 plates B', and the initial deposition of the material on the floor 21. As shown in Figure X the action results in the enfolding of the grout A' by the coarser aggregate; and the dispersion of the grout through the body of 25 the aggregate by way of fissures in the latter, and by the general folding and churning action.

The delivery of the material from the floor 21 of the truck may be by way of a chute 30 similar to that illustrated and described in connection with Figures I and VII of the drawings, or may be by other suitable form of chute providing the same constructed discharge opening.

35 What I claim is:

1. The method of reconditioning previously prepared concrete after the aggregate thereof has settled out which consists in laterally removing the supporting means 40 from a laterally confined mass of the material in a lateral manner so as to produce a constrained progressive spreading in inverse order of the strata of the same on a receiving surface.

45 2. The method of delivering previously prepared concrete after the grout thereof has been forced to the upper strata of the mass by a settling of the aggregate which consists in laterally supporting the concrete in a mass 50 having its greater horizontal area in the upper portion thereof, and permitting a spreading of the lower portion of the mass with consequent redistribution of the materials of the mass.

55 3. The method of delivering previously prepared concrete after the grout thereof has been forced to the upper strata of the mass by a settling of the aggregate which consists 60 in laterally supporting the concrete in a mass having its greater horizontal area in the upper portion thereof, and gradually laterally withdrawing the supporting means therefor and thereby permitting a gradual spreading 65 of the lower portion of the mass with

consequent reimpregnation of the aggregate by the previously separated grout.

4. The method of delivering previously prepared concrete after the thin mortar thereof has been forced to the upper strata of the mass by a settling of the coarser aggregate which consists in laterally supporting the concrete in a mass of approximately V shape in cross section, and permitting a spreading of the lower portion of the mass with consequent reimpregnation of the aggregate by the previously separated mortar. 70 75

5. The method of delivering previously prepared concrete in which the grout thereof has been forced to the upper strata of the mass by settling of the coarser aggregate which consists in laterally supporting the concrete in a mass of approximately V shape in cross section, and gradually laterally withdrawing the supporting means therefor and thereby 80 85 permitting a gradual spreading of the segregated aggregate in the lower portion of the mass with consequent reimpregnation of the aggregate by the previously separated grout.

6. The method of reconditioning concrete 90 after stratification of the aggregate and the grout thereof which consists in laterally removing the supporting means from a confined mass of the material in such manner as to produce a constrained progressive spreading 95 in inverse order of the strata of the same on a receiving surface, and discharging the material from said surface by way of a constricted passage.

7. The method of reconditioning concrete 100 after the mortar thereof has been forced to the upper strata of the mass by a settling of the coarser aggregate thereof which consists in laterally supporting such concrete mass and then laterally withdrawing such supporting 105 means to effect a folding of the aggregate upon the mortar during a deposition of such mass on a receiving surface.

8. The method of reconditioning concrete 110 after the mortar thereof has been forced to the upper strata of the mass by a settling of the coarser aggregate thereof which consists in laterally supporting the mass of concrete and then laterally withdrawing such supporting means to effect a folding of the aggregate 115 upon the mortar during a deposition of such mass on a receiving surface, and discharging the material from said surface by way of a constricted passage.

In witness whereof, I hereunto set my hand. 120
EDWARD N. JONES.
